DAIRY BAR BUILDING

Tom Triantafillou, Stuart W. Bradford, Rodolphe J. H.
La Riviere, and John Michutka, Saginaw, Mich., as
signors to Dairy Crown Corporation, Saginaw, Mich.

Application November 10, 1953, Serial No. 27,526

Term of patent 14 years

(Cl. D13—1)

F-1

To all whom it may concern:

Be it known that we, Tom Triantafillou, Stuart W. Bradford, Rodolphe J. H. La Riviere, and John Michutka, have invented a new, original, and ornamental Design for a Dairy Bar Building, of which the following is a specification, reference being had to the accompanying drawings, forming a part hereof.

In the drawings:

Fig. 1 is a front perspective view of a dairy bar building showing our new design.

Fig. 2 is a front elevational view thereof.

Fig. 3 is a rear elevational view thereof.

We claim:

The ornamental design for a dairy bar building, as shown.
